(57) **CLAIM**

The ornamental design for insulated headwear, as shown and described.

DESCRIPTION

FIG. 1 is a front, and right-side perspective view of insulated headwear embodying my new design, illustrated on the head of an exemplary wearer shown in broken lines, which form no part of the claimed design.

FIG. 2 is a front and right-side perspective view of the insulated headwear shown in FIG. 1;

FIG. 3 is a front elevational view thereof;

FIG. 4 is a rear elevational view thereof;

FIG. 5 is a right-side elevational view thereof;

FIG. 6 is a left-side elevational view thereof;

FIG. 7 is a top plan view thereof;

FIG. 8 is a bottom plan view thereof;

FIG. 9 is a perspective view thereof, similar to FIG. 1., wherein a portion of the insulated headwear has been turned up for warmer conditions;

FIG. 10 is a front and right-side perspective view thereof;

FIG. 11 is a front elevational view thereof;

FIG. 12 is a rear elevational view thereof;

FIG. 13 is a right-side elevational view thereof;

FIG. 14 is left-side elevational view thereof;

FIG. 15 is a top plan view thereof; and,

FIG. 16 is a bottom plan view thereof.
